DESIGN FOR A BOWLING SIGN

John A. Rohan, Jr., St. Louis, Mo., assignor to Regina Bowling Alley Corporation, St. Louis,
Mo., a corporation of Missouri

Application January 30, 1942, Serial No. 105,523

Term of patent 14 years

To all whom it may concern:

Be it known that I, John A. Rohan, Jr., a citizen of the United States, residing in the city of St. Louis and State of Missouri, have invented a new, original and ornamental Design for Bowling Signs, of which the following is a specification, reference being had to the accompanying drawing, forming part thereof.

Fig. 1 is a front view of a bowling sign, showing my new design.

Fig. 2 is a side view of the article shown in Fig. 1.

I claim:

The ornamental design for a bowling sign, substantially as shown.

JOHN A. ROHAN, JR.
